Primary Examiner—T. Chase Nelson*Assistant Examiner*—Kathleen M Sims(74) *Attorney, Agent, or Firm*—Cowan, Liebowitz & Latman, PC**CLAIM**

The ornamental design for the assembly of sock components, as shown and described.

DESCRIPTION

FIG. 1 is a front, top and left side perspective view of the assembly of sock components;

FIG. 2 is a rear, bottom and right side perspective view thereof; and,

FIG. 3 is a left side view thereof.

The broken lines in the Figures are for illustrative purposes only and forms no part of the claimed design.
